UNITED STATES PATENT OFFICE.

DANIEL DRAWBAUGH, OF EBERLYS MILLS, PENNSYLVANIA.

WIRELESS SIGNALING.

SPECIFICATION forming part of Letters Patent No. 752,533, dated February 16, 1904.

Application filed March 1, 1902. Renewed July 15, 1903. Serial No. 165,660. (No model.)

To all whom it may concern:

Be it known that I, DANIEL DRAWBAUGH, a citizen of the United States, residing at Eberlys Mills, in the county of Cumberland and 5 State of Pennsylvania, have invented certain new and useful Improvements in Wireless Signaling, of which the following is a specification.

The invention is an apparatus for transmitting intelligence through the natural media. 10 The method disclosed forms the subject-matter of my copending application, Serial No. 165,663.

To attain these ends the invention consists 15 of a system of wireless telephony and telegraphy embodying novel features of construction and combination of parts substantially as disclosed herein.

In the accompanying drawings, Figure 1 is 20 a diagrammatical view of my telegraphy system. Fig. 2 is a similar view of my telephony system. Fig. 3 is a similar view of a telegraphy system employing a series of stations. Fig. 4 is a side elevation of a magneto-generator and inducer employed in connection 25 with my system. Fig. 5 is a top plan view thereof with the upper portion of the magnets removed or broken away, the electrical connections being shown in diagram. Fig. 30 6 is a section taken on line $\alpha\alpha$ of Fig. 5.

Referring by numerals to the drawings, the numeral 1 designates the ground-plates of the transmitter, which are placed in the ground deep enough to always be surrounded by some 35 moisture and preferably forty, fifty, or sixty feet apart. In the telegraphy system I connect the wire 2 to a transmitting-key 3, a wire 4 connecting the key to the magneto-generator and inducer 5, which is also connected to 40 the other ground by means of the wire 6.

This is the complete transmitter. The receiver consists of the ground-plates 7 and 8, which are sunken in the earth about the same distance as the plates of the transmitter; but, 45 strange to say, to make the apparatus operative so that signals may be transmitted the plate 8 apparently must be either in advance or behind the line of the plate 7, preferably about ten feet. To the plate 7 I connect a 50 conductor-wire 9, which is connected to a re-

lay 10, a wire 11 connecting the relay to the plate 8. Operated by the relay is the receiving-instrument circuit 12. This is the complete receiver.

In order that signals may be transmitted, 55 the magneto-generator is constantly revolved by means of the motor 13, thus impressing on the wires 2 and 6, the plates 1, 7, and 8, and the wires 9 and 11 a current which when broken by the key 3 causes the relay to open 60 and close the receiving-instrument circuit, and thus cause signals to be obtained in the receiving instrument.

The magneto-generator and inducer I will 65 describe more in detail hereinafter in order that I may pass on and describe the systems.

In Fig. 3 it will be observed that I employ a single station in which the magneto-generator is connected, the other stations 14, 15, and 16 having their transmitting-current furnished by the magneto-generator in the station marked T, said magneto-generator being constantly revolved to furnish a means whereby the Morse code may be transmitted. 70

I will now pass to the description of Fig. 2, 75 wherein is shown my system of telephony. In this I employ the ground-plates 18 and the wires 19, each of which has connected thereto the switches 20, which before the telephone is ready for use connect the magneto-generator 21 with the plates. Adapted to be connected with the ground-plates at the proper time are the wires 22, which are the conductors for the telephone-transmitter 23, which includes batteries and accessory apparatus. The 80 plates and both stations are installed substantially the same distances and in the same relation to one another as in the telegraphy system, except that the telephone-transmitter and receiver are employed. Therefore in the receiving-station I have the ground-plates 24 and the telephone-receiver 25, connected thereto by its conductor-wires 26. When using the system of telephony, the transmitter is cut out from the ground-plates and the magneto-generator is placed in connection with the ground-plates. The magneto-generator is 85 now set in operation for a short space of time, say two or three minutes, when it is cut from connection with the ground-plates and the tele- 90

95 100

phone-transmitter is placed in connection with the ground-plates. The voice then spoken into the mouthpiece of the transmitter is plainly audible in the receiver, and words spoken can be easily heard and understood at a distance from one hundred feet to four miles. I have found by actual experimenting that while the magneto-generator is in operation the telegraph can be used; but as soon as the same is disconnected from the plates and the telephone-transmitter substituted the telephone can be used and has been used every day for three weeks without again necessitating the employment of the magneto-generator and inducer. It is also possible, and I have the apparatus in operative condition, for the telephone-transmitter and telegraph-transmitter to be connected directly at the same end of the line, at which time the key may be closed as when receiving a message.

In Figs. 4, 5, and 6 I have illustrated in detail and on an enlarged scale my magneto-generator, which I claim makes my system of telephony and telegraphy possible and which I have found can also be employed with any of the various systems of wireless telegraphy now in use, in which case the spark-coil and its circuit are dispensed with.

By experimenting I find that in telegraphing it was possible to get results with a Hertz oscillator, the primary circuit of which had a rapidly-operating make and break; but much better and comparatively entirely satisfactory results were attained by employing my special form of magneto. I also found that with the wires thirty feet in the air and the other terminal in the ground at both stations I obtained results far superior to those obtained with the spark-coils now used and, furthermore, that all the batteries were dispensed with. This particular subject-matter has been canceled from this specification and is the subject-matter of two applications, Serial Nos. 113,888 and 113,889, filed July 1, 1902.

The magneto-generator is constructed as follows: Upon the base 29 is mounted the two similar supporting-plates 30, which are provided with the inner concaved or curved walls 31. Supported by these plates, between the ends thereof, are the two circular disks 32, provided with the alined bearings 33 and the vertical arms 34. Mounted revolvably in the bearings of the disks is the shaft 35, carrying the oppositely-arranged arms 36, around which are wound the coils 36', which are connected to the shaft. Carried by the arms outside of the coils are the two long outwardly-curved plates 37, which are adapted to revolve with the shaft 35, the inner walls of the supporting-plates through the medium of the shaft 38 carrying the large gear 39, which meshes with the smaller gear 40 of the shaft 35. To revolve the shaft 38, any motive power may be employed, but more especially a high-speed motor. Straddling the device and having their

ends contacted upon the outer faces of the supporting-plates are the two pairs of horse-shoe-magnets 41, which are held in the proper place by means of the tie-rod 42. Secured upon the base is a rigid spring-contact plate 43, to which is connected a conductor-wire 43', passing through the base and being connected to the binding-post 44, having the flat contact-plate 45 on the upper face of the base. This contact-plate has its free end 43" in contact continuously with the inner end of the shaft 35. Mounted upon the base is also the plate 46, to which is pivotally connected the vertical switch 47, which is adapted to engage the outer face of one of the permanent magnets. Connected to the plate 46 and passing through the base to the binding-post 48 is a conductor-wire 49. I employ a switch 50 to contact the plate 45, the wire 51 connecting the binding-post 52 and the vertical post or standard 53. A flat spring 54 is adjustably held by the post 53 and is adapted to be attracted by the armature as it revolves to short-circuit the armature and to break the circuit after the armature has reached its highest point of potential. In the operation of this machine it has been found that as each one of the plates 37 passes below the spring-plate until its central point is reached the spring-plate is not affected, yet just a short distance beyond that point or when the curved plate is leaving the supporting-plate the free end of the spring-plate is caused to dip and contact the surface of the curved plate, thus short-circuiting the armature and causing a current to be transmitted to the earth-plates when the short circuit breaks twice every full revolution.

In the operation of a telegraph system my generator is constantly revolved. The faster it revolves the higher the potential, and consequently the greater current for transmission of signals. By pressing upon the key in the transmitter and operating it in the same way as in the wire telegraphs "dots" and "dashes" are readily transmitted and can be detected either in a microphone or a sounder very accurately and as speedily as with the present forms of telegraph. In my experiments I have telegraphed and received intelligent messages from distances from sixty feet to ten miles, this being done at my home and before different parties. I would also say that I have used the receiver upon a small boat in a stream, the plates being suspended in the water at approximately the distance apart as on land, and until the position of the plates were changed signals were received either by a sounder or microphone. This system may be also applied to railway-cars, where the ground connections may be made upon opposite rails by making a connection with the axles and wheels and by a small wheel carried upon the end of a long pole, which may run upon one of the two tracks or a third to one side, but must be extended beyond the rear of the car, where the relative

positions may be kept. In this system I could telegraph different distances, from sixty feet to ten miles, while the receiver was being moved along on the track.

5 I have found by experience that by operating the magneto-machine the natural media or earth becomes polarized or affected in a manner which I do not attempt to explain, so that the resistance thereof is reduced to allow 10 the transmission of low-tension currents therethrough, this being the broad principle of my invention.

What I claim as new, and desire to secure by Letters Patent, is—

15 1. In a system for the transmission of intelligence through the natural media, means for impressing on the media currents of high potential, in combination with means for impressing on the media currents modified in accordance with the signal to be transmitted.

20 2. In a system for the transmission of intelligence through the natural media, means for impressing on the media, intermittent currents of high potential, in combination with means for impressing on the media currents modified in accordance with the signal to be transmitted.

25 3. In a system for the transmission of intelligence through the natural media, means for impressing on the media alternating currents of high potential in combination with means for impressing on the media currents modified in accordance with the signal to be transmitted.

30 4. In a system for the transmission of speech through the natural media, means for impressing on the media currents of high potential, in combination with means for impressing on said media currents modified by and in accordance with sound-waves.

35 5. In a system for the transmission of speech through the natural media, means for impressing on the media intermittent currents of high potential, in combination with means for impressing on said media currents modified by and in accordance with sound-waves.

40 6. In a system for the transmission of speech through the natural media, means for impressing on the media alternating currents of high potential, in combination with means for impressing on said media currents modified by and in accordance with sound-waves.

45 7. In a system for the transmission of intelligence through the natural media, means for impressing on the media currents of high potential, in combination with means for impressing on the media currents modified in accordance with the signal to be transmitted, and means for translating said modified currents into audible or visual signals.

50 8. In a system for the transmission of intelligence through the natural media, means for impressing on the media, intermittent currents of high potential, in combination with means for impressing on the media currents modified in accordance with the signal to be transmitted, and means for translating said

55 modified currents into audible or visual signals.

9. In a system for the transmission of intelligence through the natural media, means for impressing on the media alternating currents of high potential, in combination with means for impressing on the media currents modified in accordance with the signal to be transmitted, and means for translating said modified currents into audible or visual signals. 70

10. In a system for the transmission of speech through the natural media, means for impressing on the media currents of high potential, in combination with means for impressing on said media currents modified by and in accordance with sound-waves, and means for translating said modified currents into speech. 75

11. In a system for the transmission of speech through the natural media, means for impressing on the media intermittent currents of high potential, in combination with means for impressing on said media currents modified by and in accordance with sound-waves, and means for translating said modified currents into speech. 80

12. In a system for the transmission of speech through the natural media, means for impressing on the media alternating currents of high potential, in combination with means for impressing on said media currents modified by and in accordance with sound-waves, and means for translating said modified currents into speech. 85

13. In a system for the transmission of intelligence, through the natural media, means for impressing on the media, currents of high potential, in combination with means for impressing on the media currents modified in accordance with the signal to be transmitted, and means for receiving the same. 90

14. In a system for the transmission of intelligence through the natural media, means for impressing on the media, currents of high potential, in combination with means for impressing on the media currents modified in accordance with the signal to be transmitted, and a telephone-receiver for receiving said modified currents. 110

15. In a system for the transmission of speech through the natural media, means for impressing on the media currents of high potential, in combination with means for impressing on said media currents modified by and in accordance with sound-waves, and a telephone-receiver for translating said modified currents into speech. 115

16. In a system for the transmission of intelligence through the natural media, two metal plates in said media, means for impressing on said plates electrical currents of high potential, and means for impressing on said plates currents modified in accordance with the signal to be transmitted. 125

17. In a system for the transmission of intel- 130

ligence through the natural media, two metal plates in said media, means for impressing on said plates intermittent currents of high potential, and means for impressing on said plates currents modified in accordance with the signal to be transmitted.

18. In a system for the transmission of intelligence through the natural media, two metal plates in said media, means for impressing on said plates alternating currents of high potential, and means for impressing on said plates currents modified in accordance with the signal to be transmitted.

19. In a system for the transmission of intelligence through the natural media, two metal plates in said media, means for impressing on said plates electrical currents of high potential, means for impressing on said plates currents modified in accordance with the signal to be transmitted, and two metal plates in the media at the receiving-station and a receiver connected therewith.

20. In a system for the transmission of intelligence through the natural media, two metal plates in said media, means for impressing on said plates intermittent currents of high potential, means for impressing on said plates currents modified in accordance with the signal to be transmitted, two metal plates in the media at the receiving-station, and a receiver connected to the two metal plates.

21. In a system for the transmission of intelligence through the natural media, two metal plates in said media, means for impressing on said plates currents of high potential, a source of current and means for modifying said latter current by and in accordance with the signal to be transmitted and for impressing said modified currents on said plates.

22. In a system for the transmission of intelligence through the natural media, two metal plates in said media, means for impressing on said plates alternating currents of high potential, means for impressing on said plates currents modified in accordance with the signal to be transmitted, two metal plates in the media at the receiving-station, and a receiver connected thereto.

23. In a system for the transmission of speech through the natural media, two metal plates in said media, means for impressing on said plates currents of high potential, a source of current and means for modifying said latter current by and in accordance with sound-waves and for impressing said modified currents on said plates.

24. In a system for the transmission of speech through the natural media, two metal plates in said media, means for impressing on said plates intermittent currents of high potential, a source of current and means for modifying said latter current by and in accordance with sound-waves, and for impressing said modified currents on said plates.

25. In a system for the transmission of

speech through the natural media, two metal plates in said media, means for impressing on said plates alternating currents of high potential, a source of current and means for modifying said latter current by and in accordance with sound-waves, and for impressing said modified current on said plates.

26. In a system for the transmission of speech through the natural media, two metal plates in said media, means for impressing on said plates currents of high potential, a source of current and means for modifying said latter current by and in accordance with sound-waves, and for impressing said modified currents on said plates, and two metal plates in the media at the receiving-station and a receiver connected thereto.

27. In a system for the transmission of speech through the natural media, two metal plates in said media, means for impressing on said plates intermittent currents of high potential, a source of current and means for modifying said latter current by and in accordance with sound-waves, and for impressing said modified currents on said plates, and two metal plates in the media at the receiving-station and a receiver connected thereto.

28. In a system for the transmission of speech through the natural media, two metal plates in said media, means for impressing on said metal plates alternating currents of high potential, a source of current and means for modifying said latter current by and in accordance with sound-waves, and for impressing said modified currents on said plates, and two metal plates in the media at the receiving-station and a receiver connected thereto.

29. In a system for the transmission of intelligence through the natural media, two metal plates in said receiver, means for impressing on said plates electric currents of high potential, means for impressing on said plates currents modified in accordance with the signal to be transmitted, and two metal plates at the receiving-station and a receiver connected thereto, the line joining said plates forming an angle with the line joining said first-mentioned plates.

30. In a system for the transmission of intelligence through the natural media, two metal plates in said media, means for impressing on said plates intermittent currents of high potential, means for impressing on said plates currents modified in accordance with the signal to be transmitted, and two metal plates at the receiving-station and a receiver connected thereto, the line joining said plates forming an angle with the line joining said first-mentioned plates.

31. In a system for the transmission of intelligence through the natural media, two metal plates in said media, means for impressing on said plates alternating currents of high potential, means for impressing on said plates currents modified in accordance with the signal to be transmitted.

nal to be transmitted, and two metal plates at the receiving-station and a receiver connected thereto, the line joining said plates forming an angle with the line joining said first-mentioned plates.

32. In a system for the transmission of speech through the natural media, two metal plates in said media, means for impressing on said plates currents of high potential, a source of current and means for modifying said latter current, by and in accordance with sound-waves, and for impressing said modified current on said plates, and two metal plates at the receiving-station and a receiver connected thereto, the line joining said plates forming an angle with the line joining said first-mentioned plates.

33. In a system for the transmission of speech through the natural media, two metal plates in said media, means for impressing on said plates intermittent currents of high potential, a source of current and means for modifying said latter current by and in accordance with sound-waves, and for impressing said modified current on said plates, and two metal plates at the receiving-station and a receiver connected thereto, the line joining said plates forming an angle with the line joining said first-mentioned plates.

34. In a system for the transmission of speech through the natural media, two metal plates in said media, means for impressing on said plates alternating currents of high potential, a source of current and means for modifying said latter current by and in accordance with sound-waves, and for impressing said modified current on said plates, and two metal plates at the receiving-station and a receiver connected thereto, the line joining said plates forming an angle with the line joining said first-mentioned plates.

35. In a system for the transmission of intelligence through the natural media, the combination of two metal plates in said media, means for impressing on said plates currents of high potential, means for impressing on said plates currents modified in accordance with the signal to be sent, and means for connecting to the plates one of the current-impressing means and at the same time disconnecting therefrom the other current-impressing means.

36. In a system for the transmission of intelligence through the natural media, the combination of two metal plates in said media, means for impressing on said plates currents modified in accordance with the signal to be sent, and a switch for connecting to the plates one of the current-impressing means and at the same time disconnecting therefrom the other current-impressing means.

37. In a system for the transmission of speech through the natural media, the combination of two metal plates in said media, means

for impressing on the said plates currents of high potential, a source of current, means for modifying said current by and in accordance with sound-waves and for impressing said modified currents on said plates, and means for connecting to the plates one of the current-impressing means and simultaneously disconnecting therefrom the other current-impressing means.

38. In a system for the transmission of speech through the natural media, the combination of two metal plates in said media, means for impressing on said plates currents of high potential, a source of current, means for modifying said current by and in accordance with sound-waves and for impressing said modified currents on said plates, and a switch for connecting to the plates one of the current-impressing means and simultaneously disconnecting therefrom the other current-impressing means.

39. In a system for the transmission of intelligence through the natural media, the combination of a magneto-generator for impressing on said media currents of high potential, a source of current, and means for modifying said current in accordance with the signal to be sent and for impressing said modified current on said media.

40. In a system for the transmission of intelligence through the natural media, the combination of a magneto-generator for impressing on said media currents of high potential, a source of current, means for modifying said current in accordance with the signal to be sent and for impressing said modified current on said media, and means for alternately connecting said generator and said last-mentioned means to said media.

41. In a system for the transmission of intelligence through the natural media, the combination of a magneto-generator for impressing on said media currents of high potential, a source of current, a telephone-transmitter for modifying said current in accordance with the signal to be sent, and for impressing said modified currents on said media, and means for alternately connecting said generator and said transmitter to said media.

42. In a system for the transmission of intelligence through the natural media, the combination of means for polarizing the media, and means for impressing on the media currents modified in accordance with the signal to be sent.

43. In a system for the transmission of intelligence through the natural media, the combination of means for polarizing the media, means for impressing on the media currents modified in accordance with the signal to be sent, and a receiver at a distant station for receiving the same.

44. In a system for the transmission of speech through the natural media, the combi-

- nation of means for polarizing the media, and means for impressing on the media currents modified by and in accordance with sound-waves. 65.
5. 45. In a system for the transmission of speech through the natural media, the combination of means for polarizing the media, means for impressing on the media currents modified by and in accordance with sound-waves, and a receiver at a distant station for receiving the same. 70
10. 46. In a system for the transmission of intelligence through the natural media, the combination of a magneto-generator, means for connecting said generator to the media, and means for short-circuiting said generator at the point of maximum potential of the current generated thereby, so that currents of high potential may be impressed on the media. 75
15. 47. In a system for the transmission of intelligence through the natural media, the combination of a magneto-generator, means for connecting said generator to the media, and a spring-plate of magnetic material for short-circuiting said generator at the point of maximum potential of the current generated thereby, so that currents of high potential may be impressed on the media. 80
20. 48. In a system for the transmission of intelligence through the natural media, means for polarizing the media between the transmitting and receiving station, said means comprising a magneto-generator having means for short-circuiting the current generated thereby at the point of maximum potential of said current. 85
25. 49. In a system for the transmission of intelligence through the natural media, means for polarizing the media between the transmitting and receiving station, said means comprising a magneto-generator having a spring-plate of magnetic material for short-circuiting the current generated thereby at the point of maximum potential of said current. 90
30. 50. In a system for the transmission of speech through the earth, the combination of two metal plates in the earth a magneto-generator for impressing on said plates currents of high potential, means for short-circuiting said generator at the point of maximum potential, a transmitter for impressing on the plates currents modified by and in accordance with sound-waves, a switch for alternately connecting said generator and said transmitter to the plates, and two plates at the distant station so positioned in the earth that the line joining them forms a small angle with the line joining the two first-mentioned plates, and a telephone-receiver connected to said plates. 95
35. 51. In a system for the transmission of speech through the natural media, the combination of means for polarizing the media between the transmitting and receiving stations and means for impressing thereon currents modified by and in accordance with sound-waves. 100
52. In a system for the transmission of speech through the earth, the combination of means for polarizing the earth between the transmitting and receiving stations, and means for impressing thereon currents modified by and in accordance with sound-waves. 105
53. In an apparatus of the character described, the combination of means for preparing the earth so that undulatory waves can be transmitted through the earth and means for generating said undulatory waves. 110
54. In an apparatus of the character described, the combination of means for preparing the natural media, so that undulatory waves can be transmitted through the natural media and means for generating said undulatory waves. 115
55. In a system of telephony, the combination of two ground connections and a transmitting instrument connected therewith, a receiver having two ground connections, and means to impress on the ground at the transmitter currents of high potential, and means for impressing on said plates currents modified by and in accordance with sound-waves. 120
56. In a system of wireless telephony, a transmitter and a receiver, each having two ground connections, a magneto-generator connected to the transmitter's ground connections to impress a high-potential current on said connections, and means to cut the magneto-generator from connection with the ground connections when the transmitter is connected with the ground. 125
57. In a system of wireless telephony having two ground connections at the transmitting and receiving stations, a magneto-generator connected to the ground connections of the transmitting-station to impress a high-potential current upon said connections, a transmitter, and means to disconnect the generator from the ground connections when the transmitter is connected to the ground connections. 130
58. In a transmitter, the combination of two ground connections, means to make a signal and means to establish an electrical circuit, said means comprising a pair of supporting-plates, a field-magnet surrounding the same, a revolving armature mounted between the said supporting-plates, a spring-plate suspended above the supporting-plates and armature, and electrical connections between the armature and one connection of the transmitter and between the spring-plate, magnet and the other connection of the transmitter. 135
59. In a signaling system, the combination of a transmitter which comprises two connections with the natural media, means to produce a signal, and means to impress a high-potential current upon the natural media, said means comprising a magneto-machine, whose armature is adapted to be revolved, and means 140

to short circuit the armature for automatically breaking the circuit when the current is at its maximum.

60. In transmitter apparatus for transmitting intelligence through natural medium or media, means for impressing high-potential electric impulses thereupon, and means for transmitting an undulatory variation in cor-

respondence with speech, for substantially the purposes set forth.

In testimony whereof I affix my signature in presence of two witnesses:

DANIEL DRAWBAUGH.
